SAFETY WRENCH

Roy B. Wellborn, James L. Dye, and Neigel R.
Perry, Osage, Okla.

Application May 17, 1939, Serial No. 274,136

4 Claims. (Cl. 255—35)

This invention relates to wrenches and particularly to safety wrenches for unscrewing and for making up long lengths of pump rods, tubing, pipe, and the like in deep wells.

When pump rods, tubing or pipe have been made up tightly in long strings, and especially when they have been in place in wells for long periods of time, the screwed joints thereof become very tight or "frozen" and become very difficult to unscrew. Also very often, the pump, which is located far down in the well, becomes stuck there and it becomes impossible to withdraw it so that the pump rods cannot be pulled up and unscrewed joint-by-joint as they are withdrawn from the well. Under such conditions it is generally desirable to unscrew the rods as far down in the well as possible, without removing the well pipe or tubing in which the rods are normally inserted. When an attempt is made to unscrew such long lengths of rods by turning of the upper end thereof, the rods will twist through a great many revolutions and considerable torque stress will be set-up therein before the threads of any joint down in the well begins to give way. Under such conditions, when the upper end of the string of rods has been turned a number of revolutions, the effect is similar to coiling a powerful helical spring so that if the upper end of the rod string is released or flies out of the grip of the men turning the rods, a rapid and powerful uncoiling of the rods occurs, due to the torsional stress set up therein, and may, as frequently happens, result in injury to the workers. The same situation applies when making up long strings of rods, tubing, pipe and the like.

A principal object of this invention, therefore, is to provide an apparatus designed to permit unscrewing or making-up of long strings of rods, tubing, pipe, and the like in deep wells, while retaining the twist of the strings under full control at all times, so that the turning of the strings may be stopped at any time during the operation without releasing the strings and the normal "back-lash" of such strings maintained under full control of the operators at all times.

Another object is to provide a safety wrench for unscrewing or making-up long strings of well rods, tubing, and pipe, whereby the normal "back-lash" thereof is held under full control and controllably released to produce a sharp jarring of the strings to effect release or tightening of the screwed joints of the strings as may be desired.

Another important object is to provide a safety

wrench for the unscrewing or making-up of long lengths of well rods, tubing pipe, and the like, which is simple in operation and provides positive control of the torsional "back-lash" of the strings.

Still another object is to provide a safety wrench for unscrewing jointed strings of well pump rods without removing the well pipe in which they are normally inserted.

Additional important objects of this invention will be readily apparent from the following detailed description, when read in conjunction with the accompanying drawings which illustrate a preferred modification of the invention.

In the drawings:

Fig. 1 is an assembly of the device mounted on a well pipe and shown partly in longitudinal section.

Fig. 2 is a top view of the assembled device of Fig. 1.

Fig. 3 is a longitudinal section through the wrench proper.

Fig. 4 is a plan view taken along line 4—4 of Fig. 3.

Fig. 5 is a longitudinal section of the wrench case.

Fig. 6 is a top view of the wrench case, and

Fig. 7 is a general assembly in place on top of a well pipe.

Referring to the drawings, the device consists of a cylindrical casing 1 made in two half-sections which are hinged together at one side by means of hinges 6—6 and provided at the opposite sides with registering apertured ears 6a—6a adapted to receive locking pins 6b—6b for locking the two sections together. Casing 1 is provided near its lower end with an interior partition 2 having an axial opening 3 therethrough. Below partition 2 and seated in suitable recesses 4a in the inner wall of casing 1 are oppositely disposed toothed jaws 4—4, which are adapted to be advanced and retracted radially within casing 1 by means of adjusting screws 5—5. A pair of diametrically opposed ribs 7—7 are formed or rigidly attached to the inner wall of casing 1 above partition 2, one of the ribs 7 being in each half of the casing and extends longitudinally thereof above partition 2.

A sleeve type wrench, generally tubular in construction and designated by the numeral 8, is also formed in half sections and has a central bore 9 therethrough adapted to enclose a well rod R. The wrench may be employed on tubing or pipe equally as well as rod R. The outer diameter of the lower portion 10 of wrench 8 is 55

such that the lower portion 10 will pass freely through the opening 3 and act as a guide for insertion of the wrench into casing 1. The bore at the upper end of wrench 8 is enlarged and recessed at 9a to receive a fixed toothed die 11 and an oppositely disposed movable die 12 which is provided with a shank 13 which extends through an opening 9b in the wall of the wrench. The shank 13 is threaded and provided with an adjusting nut 14. By adjustment of movable die 12 by means of nut 14, the movable die 12 will co-act with fixed die 11 to grip rod R which is enclosed by the wrench (Figs. 1 and 2). A pair of oppositely disposed handles 15—15 extend laterally from opposite sides of the upper end of wrench 8, and are used to turn the wrench and the rod being gripped thereby.

A ratchet wheel 16 is also made in half sections, each of which is provided with laterally projecting apertured ears 17—17 registering with each other and adapted to be joined together by means of pins 17a. Wheel 16 is provided with a central bore adapted to receive therein a reduced intermediate portion of the wrench, wherefore by wrench 8 and wheel 16 will be rotatable relative to each other. The diameter of wheel 16 is less than the diametric distance between ribs 7—7 and the ears 17—17 project sufficiently from the periphery of wheel 16 to engage ribs 7, which thus form stops for limiting the rotation of the ratchet wheel.

The upper face of ratchet wheel 16 is provided with two concentric circular rows of ratchet teeth, the teeth of the outer row being designated 18, and those of the inner row 19, which face in the opposite direction to teeth 18.

A pair of pawls 20—20 engage the teeth 18 on opposite sides of wrench 8 and are pivoted on oppositely disposed shafts 21—21 which extend laterally from opposite sides of wrench 8. A second pair of pawls 22—22 similarly engage the teeth 19 and are similarly pivoted on shafts 21—21 but face opposite directions to pawls 20—20. Chains 23—23 attached to opposite sides of wrench 8 are adapted to be attached to eyes 24—24 mounted on pawls 20 and 22 when it is desired to lift any or all of the pawls out of their normal engagement with teeth 18 and 19 respectively.

The operation of the device may be exemplified by describing the removal of well pump rods from a well where the tubing or well pipe P is to be kept in place. It will be understood that the operation is similarly applicable to the removal of tubing or the inner strings of well pipe, where an outer string of pipe or casing remains in place in the well.

The two halves of casing 1 are placed about the upper end of well pipe P from which the rods are to be withdrawn and when the sections of the casing have been locked together by means of pins 6b, the jaws 4—4 are advanced by means of screws 5—5 to securely grip the upper end of pipe P. The two half sections of wrench 8 including ratchet wheel 16, are then placed about the upper end of rod R projecting above the top of casing 1 and are locked together by locking together the half sections of wheel 16 by insertion of pins 17a into the registering aperture of ears 17—17. The upper end of rod R passes between dies 11 and 12, the latter being in the open or non-gripping position at this time. The assembled wrench is then slipped down rod R until the lower portion 10 passes through opening 3 and is inserted into the annular space between rod R and

the inner wall of pipe P, being advanced therein until the lower face of ratchet wheel 16 comes to rest on the upper face of partition 2. Movable die 12 is then adjusted by means of nut 14 until the rod R is tightly gripped between the dies 11 and 12. 5

If the rods are to be unscrewed, the usual case, pawls 22—22 are lifted and held out of engagement with the teeth 19 by hooking chains 23 to eyes 24.

Pawls 20—20 are left in engagement with the teeth 18. The handles 15—15 are then turned to unscrew the rod sections. As the turning progresses, ears 17—17 engage ribs 7—7 and brings ratchet wheel 16 to a stop, while rotation of the wrench 8 and rod R continues, pawls 20—20 slipping over teeth 18 during this movement. Reverse rotation of the rods under the torsion developed therein is effectively prevented by the engagement of pawls 20 with teeth 18 when such movement occurs and by the limiting action resulting from the engagement of ears 17 with ribs 7 when a half-turn of the wheel 16 takes place. This reverse rotation may be held back by the men at the handles 15 to allow ears 17 to come to rest easily against ribs 7. However, it is frequently desirable to jar the string of rods when they have been twisted to a suitable extent, as it is found that such a jar will usually start the unscrewing of the rod joints where a steady pull is ineffective. Under these conditions the handles 15 may be released suddenly with the result that the following reverse half-rotation of the wrench between ribs 7—7 takes place under the full force of the torsional stress in the rods and the resulting contact of ears 17—17 with ribs 7—7 takes place with considerable force and produces a sharp blow or jar which is transmitted to the rod string and is very effective to start the unscrewing of the rod joints generally at the lowest joint which is subjected to the twist of the rods. At 40 the same time the amount of "back-lash" thus permitted is positively limited, and is under safe control at all times.

The device may be similarly used to make up and break-out tubing and pipe. When making-up rods or pipe, pawls 20 are held out of engagement with teeth 18 and pawls 22—22 engage with teeth 19.

It will be understood that all of the parts of the described device are preferably constructed 50 of steel or other strong metals suitable for withstanding the stresses and strains to which it is subjected in operation. Ratchet wheel 16 may be provided with teeth on both faces thereof so that if those on one side become worn or broken it 55 is only necessary to reverse the wheel to have new teeth available.

Numerous modifications and alterations may be made in the size, form and details of the parts of the structure of this invention without departing from the scope of the appended claims.

What we claim and desire to secure by Letters Patent is:

1. A wrench for unscrewing or making up a screw-jointed string of rods or tubing within an outer pipe comprising, a cylindrical casing adapted to be fixedly attached to the upper end of said outer pipe and surrounding said string, a sleeve member insertable axially of said casing and having a hollow bore adapted to enclose said rods or tubing, gripping means positioned in the bore of said sleeve member and adapted to grip said rods or tubing, means for rotating said sleeve member relative to said casing, and latch means operative between said sleeve member and said cas- 75

ing to positively limit reverse rotation of said sleeve member induced by torsional stress developed in said rods or tubing by rotation of said sleeve member.

5. 2. A wrench for unscrewing or making-up a screw-jointed string of rods or tubing within an outer pipe comprising, a cylindrical casing adapted to be fixedly attached to the upper end of said outer pipe and surrounding said string, longitudinal stop members positioned on the inner wall of said casing, a sleeve member insertable in said casing and having a hollow bore adapted to enclose said rods or tubing, gripping means positioned in the bore of said sleeve and adapted to grip said rods or tubing, means for rotating said sleeve member relative to said casing, and latch means carried by said sleeve member cooperating with said stop members to positively limit reverse rotation of said sleeve member induced by 10 torsional stress developed in said rods or tubing by the forward rotation of said sleeve member.

3. A wrench for unscrewing or making up a screw-jointed string of rods or tubing within an outer pipe comprising, a cylindrical casing adapted to be fixedly attached to the upper end of said outer pipe and surrounding said string, longitudinal stop members positioned on the inner wall of said casing, a sleeve member insertable in said casing and having a hollow bore adapted to enclose said rods or tubing, adjustable gripping means positioned in the bore of said sleeve member and adapted to grip said rods or tubing, means for rotating said sleeve member relative to said

casing, and latch means carried by said sleeve member cooperating with said stop members to positively limit reverse rotation of said sleeve member induced by torsional stress developed in said rods or tubing by the forward rotation of 5 said sleeve member, said latch means comprising an annular ratchet surrounding said sleeve member, and rotatable relative thereto, projections extending laterally from the periphery of said ratchet, and pawls carried by said sleeve member 10 and cooperating with said ratchet to force said ratchet to rotate with said sleeve member.

4. A wrench of the class described comprising, a hollow cylindrical casing, toothed jaws adjustably mounted in the lower end thereof, radial 15 projections extending longitudinally along the inner wall of said casing, a hollow sleeve member insertable axially of said casing and rotatable relative thereto, gripping means positioned in the bore of said sleeve member, means for rotating 20 said sleeve member relative to said casing, a horizontally positioned annular disk carried by said sleeve member and rotatable relative thereto, spaced projections extending laterally from the periphery of said disk into engagement with said 25 radial projections in the casing, ratchet teeth carried by said disk, and cooperating pawls carried by said sleeve member whereby said sleeve member and said disk will rotate together in one direction.
